UNITED STATES PATENT OFFICE.

ALBERT C. JACKSON, OF DAYTON, OHIO.

DESIGN FOR A COMBINATION MERCHANDISE AND ADVERTISING DISPLAY STAND.

Application filed December 31, 1924. Serial No. 11,832. Term of patent 3½ years.

To all whom it may concern:

Be it known that I, ALBERT C. JACKSON, a citizen of the United States, residing at Dayton, in the county of Montgomery and State of Ohio, have invented a new, original, and ornamental Design for a Combination Merchandise and Advertising Display Stand, of which the following is a specification, reference being had to the accompanying drawing, forming part hereof.

The figure is a perspective view of a combination merchandise and advertising display stand, showing my new design.

I claim:

The ornamental design for a combination merchandise and advertising display stand, as shown.

ALBERT C. JACKSON.

Witness:

HOWARD S. SMITH.
